Bamert Regan PLLC

(57) **CLAIM**

We claim the ornamental design for a spur washer, as shown in the drawings.

DESCRIPTION

FIG. 1 is a front isometric perspective view of a spur washer, showing the new design.

FIG. 2 is an overhead view thereof.

FIG. 3 is a left elevational view thereof.

FIG. 4 is a front elevational view thereof.

FIG. 5 is a right elevational view thereof.

FIG. 6 is a rear elevational view thereof; and,

FIG. 7 is an underside view thereof.

1 Claim, 7 Drawing Sheets
